UNITED STATES PATENT OFFICE.

WILLIAM A. COMINS AND JOSEPH CONNOR, OF STAFFORD SPRINGS,
CONNECTICUT.

HORSESHOE-CALK.

No. 813,777.

Specification of Letters Patent.

Patented Feb. 27, 1906.

Application filed July 17, 1905. Serial No. 270,131.

To all whom it may concern:

Be it known that we, **WILLIAM A. COMINS** and **JOSEPH CONNOR**, citizens of the United States, residing at Stafford Springs, in the county of Tolland and State of Connecticut, have invented certain new and useful Improvements in Horseshoe-Calks, of which the following is a specification.

Our invention relates to an improvement 10 in horseshoe-calks; and the object of our invention is to provide a calk with greater durability than the calks now in use and one which can be placed on the market at a small initial cost.

15 Our invention further consists in certain other novel features of construction and combinations of parts, which will be hereinafter described, and pointed out in the claim.

In the accompanying drawings, Figure 1 is 20 a view showing the calks applied to a horseshoe. Fig. 2 is a view of one of the calks, and Fig. 3 is a cross-section showing the hard-metal core and soft-metal exterior.

A represents the ordinary horseshoe, and 25 1 1 are holes in the shoe for the reception of the calks 2 2. The calks 2 2 are preferably made of iron and steel, the steel being placed between two pieces of iron, and when formed into a calk the steel will be in the center or 30 core of the calk and the iron will be on the outside. Of course the iron will wear faster than the steel, but the steel will always be sharp, and the calk can be hardened harder

than an all-steel calk when made in this way. The calk is preferably made in the form of an 35 isosceles triangle, and it is provided at one end with the usual threaded projection or stud 3, which is screwed into the holes 1 1 of the shoe. In the other end of the calk we have provided a V-shaped slot or notch 4. 40 By cutting this notch 4 in the calk, thereby exposing the core, we are able to harden the calk harder than has been possible heretofore, as it has been practically impossible to get the central core of the calk hard enough. 45

It will be seen from the foregoing that we have provided a calk which will be cheap to manufacture and one which will wear longer than the ordinary calk and will not pull out or give way when a hard strain is brought on it. 50

Having fully described our invention, what we claim as new, and desire to secure by Letters Patent, is—

A horseshoe-calk having a hard-metal core and a soft-metal exterior, said calk being bifurcated substantially midway of its ends, and the core being exposed in the bifurcation. 55

In testimony whereof we affix our signatures in presence of two witnesses,

WILLIAM A. COMINS,
JOSEPH CONNOR.
